UNITED STATES PATENT OFFICE.

EDWARD B. HESS, OF NEW YORK, N. Y., ASSIGNOR TO ROYAL TYPEWRITER COMPANY, OF NEW YORK, N. Y., A CORPORATION OF NEW JERSEY.

TYPE-WRITING MACHINE.

1,028,214.

Specification of Letters Patent. Patented June 4, 1912.

Application filed October 30, 1908. Serial No. 460,227.

To all whom it may concern:

Be it known that I, EDWARD B. HESS, a citizen of the United States of America, residing in the borough of Manhattan, city, county, and State of New York, have invented certain Improvements in Type-Writing Machines, of which the following is a specification.

This invention relates primarily to a front strike typewriting machine.

In Letters Patent of the United States heretofore granted to me, I have shown a breaking or accelerating toggle flexing link connection acted upon on depression of the finger piece to pull the type bar to the printing point with an increasing velocity. In machines constructed in accordance with the present invention, I employ two such flexing connections, one acted upon on depression of a finger piece and it in turn acting upon the other which is directly connected to the type bar. The result is that the accelerating breaking toggle connection acted upon by depression of the finger piece has a part acting with increasing velocity upon the second such connection which has a part acting in turn because of its own movement with an increasing acceleration upon the type bar. In a front strike typewriting machine employing two such accelerating or breaking toggle or flexing connections, the one applied to the type bar would ordinarily be disposed in rear of the type bar pivot and would most conveniently be disposed vertically and the other, acted upon on depression of the finger piece, would be connected to the first one and would most conveniently extend forward under the type bars to be acted upon either by a push pin equipped with the finger piece or a key lever. The rate of acceleration of the type bar would be equal substantially to the sum of the rates of acceleration of the two flexing connections.

In the accompanying drawings: Figure 1 is a diagrammatic view in the nature of a longitudinal vertical central section showing the employment of a push pin; Fig. 2, a

similar view showing a slightly modified construction of the push pin arrangement; Fig. 3, a similar view illustrating the employment of a key lever; Fig. 4, is a rear view showing one of the series of vertically disposed reverse toggle connections for operating the type bars; Fig. 5, a rear elevation showing the general arrangement of key levers and links; Figs. 6 and 7, similar views showing modified constructions in connection with the employment of key levers.

In Fig. 1, 1 is the platen, 2 the type bar segment, 3 one of the type bars pivoted therein and 4 a push pin to which is applied the usual finger piece. 5 is a short link hinged at its front end to a fixed point or part 5' of the frame and at its rear end to a longer link 6. In the construction shown, the hinged connection between links 5, 6, is effected by hinging both of them in the lower end of the push pin 4. The rear end of the link 6 is pivotally connected with an upright link 7 rocking about a fixed axis 8 in a segmental piece 27 and having connected with its upper end a link 9 hinged to the heel 3' of the type bar. 10 is a reaction spring applied to the link 7; and 11 is a back stop rod common to all of the links 7. This figure of the drawing shows one of the central type bars of the segment and its operating devices. In a completely assembled aggregation of type bars, operating connections and push pins, the axes 8 of the several links 7 would be arranged segmentally or in a curve corresponding generally with the segmental curve in which the axes 3, 2, of the type bars lie. This figure shows but one push pin. All others in the same bank or row of the key board will preferably be of the same length and their ends would therefore lie in substantially the same horizontal plane and it would follow that the rear ends of link 6 would occupy a segmental curve. This general arrangement would be obvious to those skilled in the art. When push pin 4 is depressed and link 5 swings about its axis 5', link 6 will be pulled

forward with an increasing speed. Similarly, as link 7 is drawn forward, it will pull down link 9 with an increasing speed. The dotted lines *a*, *b*, *c*, *d*, *e*, indicate the 5 different levels through which the end of the push pin will pass while the dotted lines *f*, *g*, *h*, indicate the different positions of the hinged connection between links 7 and 9. The double acceleration due to the employment 10 of two accelerating or breaking toggle devices is indicated at *i*, *j*, *k*, *m*. Thus, during the first quarter of depression of the finger piece, the type bar head will move through one-half of a degree; during the 15 next quarter, indicated at *j*, it will move through five and one-half degrees; during the next quarter indicated at *k* it will move through twenty degrees; and during the final quarter, as indicated at *m*, it will move 20 through sixty-four degrees. The speed of the type bar both in approaching and receding from the platen will therefore be very great. This eliminates danger of collision of the bars, affords high speed and fine 25 capacity for manifold work. The stop 11 is so placed that when the parts are at rest, the point of connection between 7 and 9 and 9 and 3' may be in line with axis 8; or if desired, the stop may be so placed that links 30 7 and 9 will incline slightly toward the rear. The result will be that the type bar will be locked against its lock stop or rest preventing rebound therefrom.

In Fig. 2 there is much the same arrangement 35 except that there is a reaction spring 12 applied directly to the type bar and from link 7' that corresponds with link 7 of Fig. 1 there extends rearwardly a hooked link 13 that engages the universal bar 14 which 40 swings about an axis 15 and is normally drawn rearwardly by a spring 16.

In Fig. 3, the parts corresponding to those in Fig. 1 are similarly lettered. In this instance, however, the front link, marked 5², is pivoted in an upright post mounted in a 45 slot in a front segmental plate 17 that is capable of adjustment by means of set screws 18. This structure has been shown in Letters Patent heretofore granted to me. In this figure, for clearness of illustration 50 the upper link 9 and horizontal link 6 are each indicated merely by a dotted line and their different positions by a series of dotted lines. Below the axis 8 of link 7 are pivoted 55 arms 19 having extending between their upper ends a universal bar 20 disposed in front of the links 7 in such position as to be acted upon thereby at the proper time. 21 is a reaction spring applied to the universal 60 bar. In the construction of Fig. 3, push pins are not employed but, on the contrary, there is a key lever 22 for each type bar having applied to it a reaction spring 23. The key levers are pivoted at 24 and adja-

cent their front up-turned ends, which are 65 equipped as usual with finger pieces, are guided in the comb plate 25. A link 26, indicated by a dotted line, extends from the key lever to link 5² being connected thereto intermediate its fixed point or axis by 5' and 70 its rear end. The several positions are indicated by dotted lines. In this construction, it is preferred that the axes 5' of all the links 5² shall be arranged in a segmental 75 curve as shown in patents heretofore granted to me and as stated in connection with Fig. 1. It is preferred that the axes 8 of the various links 7 shall be arranged in a segmental curve conforming more or less to the curve in which the axes of the type 80 bars are disposed. In this case, as in Fig. 1, there is a very high acceleration of the type bar in its excursion from its position of rest to the printing point. During the first quarter of depression of the key lever, 85 the type bar head will move through two degrees; during the next quarter, through eight degrees; during the third quarter through twenty-nine degrees; and during the final quarter through fifty-one degrees. 90 In the construction illustrated, the type bars are also locked against rebound from their rest.

Fig. 5 is a rear view showing the general 95 radial and segmental arrangement of the type bars and links 9, 7, and the disposition of links 26 extending from the key levers to the short front links 5, 2.

Fig. 6 shows an arrangement very similar to Fig. 3. The construction and operation are obvious. A reaction spring is applied under each type bar and the universal bar is located under the key levers and the reaction compression spring applied under each key lever. In the construction of Fig. 100 6, the point of connection of link 6 with link 7 is much closer the point of flexure of connection composed of the links 7 and 9 than is the case in Figs. 1 and 3.

In Fig. 7, the link 6 is connected with 105 links 9 and 7 at their point of flexure and the link 26 extending from the key lever 22 is connected directly at the point of flexure between the links 5 and 6. A reaction extension spring is applied to the 110 top of each key lever and a like reaction spring applied to the heel of each type bar.

This invention is clearly applicable either 115 to platen or segmental shift machines. Of course, in the case of platen shift any appropriate or usual form of platen or carriage shift mechanism may be employed. In the event of a segmental shift being used, the segment 27 in which are pivoted the 120 several links 7 would be rigidly connected 125 with type bar segment 2.

I claim:

A type bar actuating mechanism, com-

prising two connected breaking or accelerating toggle connections one disposed vertically between each type bar and a fixed point and the other extending forward under the type bar to a fixed point, a universal bar acted upon by the first named toggle connection and means acting on the second named toggle connection intermediate its

ends on depression of its corresponding finger piece.

In testimony whereof, I have hereunto 10
subscribed my name.

EDWARD B. HESS.
